United States Patent Office

Des. 216,264
Patented Dec. 9, 1969

216,264

NOTE HOLDER ATTACHMENT FOR A TELEPHONE

Michele Dietrich, Lafayette Hill, and William P. Godley,
Maple Glen, Pa., assignors to Honeywell Inc., Minneapolis, Minn., a corporation of Delaware

Filed Nov. 7, 1968, Ser. No. 14,345

Term of patent 14 years

Int. Cl. D14—03
U.S. Cl. D26—14

The single figure on the drawing is a perspective view of a note holder attachment for a telephone showing our new design.

We claim:

The ornamental design for a note holder attachment for a telephone, substantially as shown.
